UNITED STATES PATENT OFFICE.

RALPH H. Langley, of Schenectady, New York, assignor to General Electric Company, a corporation of New York.

VARIABLE CONDENSER.

Application filed September 26, 1923. Serial No. 665,013.

My invention relates to the construction of variable condensers comprising two sets of plates in which the plates of one set are interleaved with those of another set and are mounted to be moved relatively thereto. The object of my invention is to provide an improved construction of the condenser plates whereby accurate spacing of the plates of a set is assured without the use of separate spacing members.

5

10

My invention will be better understood by reference to the accompanying specification and drawing and its scope will be pointed out in the appended claims. In the drawing Fig. 1 is a vertical cross-sectional view of a condenser, involving my invention taken on the line 1—1 of Fig. 2; Fig. 2 is a horizontal cross-sectional view taken on the line 2—2 of Fig. 1; and Fig. 3 is a detail of one 20

of the plates drawn to a larger scale.

The condenser comprising my invention is built up of two sets of substantially semi-circular plates, a stationary set 1 and a rotatable set 2, the plates of the two sets being interleaved and relatively movable without contact. The plates comprising each set are identical. Each stationary plate is provided with three openings 3 of a size to receive the securing means, to be described later, and

25

30 the material surrounding each opening is expanded to form oppositely extending flanges 4 and 4' or what might be termed a double cup with portions extending equi-distantly from both sides of the plate. The plates may be conveniently given the desired form by a punching operation, the dies being so made that the two oppositely extending annular flanges formed in the plates have a height equal to one-half of the desired spacing of the plates.

35

40 To build up the stationary element of a condenser having plates so formed, the individual plates are stacked up with every alternate plate inverted and with the openings 3 in alinement. The stack thus formed is then placed between the two insulation plates 6 and 7 and the three securing bolts 8 passed through the alining openings in the condenser plates and through corresponding openings in the insulation plates. A suitable spacing washer 9 may be used above the top condenser plate and the set firmly secured together and to the insulation plates by nuts 10. It will be noted that by giving each plate a double cup or double flange formation such as illustrated and by

45

50

55

arranging the plates with each alternate plate inverted, corresponding flange portions of adjacent plates bear against each other. It is unnecessary therefore that the flanges be given square edges as would be the case were the flanges to extend to one side only of the plates and the plates were to be stacked up without reversing alternate plates. With this construction the plates set firmly against each other with a predetermined and accurate spacing.

60

65

The plates comprising the rotatable set are each provided with a single concentric opening 11 with the material surrounding the openings formed up into oppositely extending annular flanges just like the stationary plates. These are also stacked up with each alternate plate inverted and secured together on a spindle 12 by being clamped between a sleeve 13 and a nut 14. A knob 15 and dial 16 are shown mounted on the spindle 12 as is usual.

70

75

While I have described only one embodiment of my invention, I do not wish to be limited to the particular form shown and described as it will be apparent that many modifications therein may be made without departing from the scope of my invention as set forth in the appended claims.

80

What I claim as new and desire to secure by Letters Patent of the United States, is:

85

1. In a variable condenser, a series of parallel plates having alined openings therein, a clamping member extending therethrough, said plates having integral spacing portions adjacent said openings and extending laterally from opposite sides of the plates, the spacing portion on one side of each plate being further from the axis of the clamping element than the spacing portion on the opposite side.

90

95

2. In a variable condenser, a series of parallel plates having alining apertures therethrough and clamping means extending therethrough, said plates having spacing means comprising annular flanges extending on opposite sides thereof and surrounding said clamping means, the diameter of the flange on one side of each plate being greater than the diameter of the flange on the opposite side of the same plate.

100

105

3. In a variable condenser, a series of parallel plates having alined openings therein, a clamping rod extending therethrough, said plates having spacing means

110

- comprising a pair of integral concentric annular flanges formed therein around said openings, one of said flanges projecting at one side of a plate and the other projecting 5 at the opposite side thereof, said flanges having a height substantially equal to one-half the distance between adjacent plates, the diameter of the annular flange on one side of each plate being greater than the 10 diameter of the annular flange on the opposite side of the same plate.
4. In a variable condenser, a series of parallel plates having alined openings therein, a clamping rod extending through 15 said openings, each plate having spacing means comprising a pair of annular flanges formed integral with the plate around the axis of each opening, one of said flanges projecting beyond one side of the plate and 20 the other projecting beyond the opposite side of the plate, the diameter of the annular flange on one side of each plate being greater than the diameter of the annular flange on the opposite side of the same plate 25 said flanges forming spacing elements for the plates.
5. An electric condenser including a plate having a boss on each side of the plate, each boss being integral with the plate and 30 formed from the metal of the plate, a portion of the original surface of the plate appearing on each boss in a plane parallel to the plate said boss elements serving as spacing elements for the plate.
- 35 6. An electric condenser including a series of plates, each plate having a boss on each side thereof, each boss being integral with the plate and formed from the metal of the plate, a portion of the original surface of 40 the plate appearing on each boss in a plane parallel to the plate, said plates arranged with the axes of the boss elements coinciding and parallel with the axis of the capacitor, the boss on one plate bearing against the boss of the adjacent plate, said bosses 45 serving as spacing elements for the plates, a shaft extending through said boss elements, the axis of the shaft being parallel to the axis of the capacitor and means upon the shaft for securing said plates together 50 by pressing the boss elements together.
7. An electric condenser including a plate, a boss formed on each side of said plate from the metal of the plate, the metal of the plate being folded in one direction along the longitudinal axis of the plate and then folded back in the opposite direction along the axis of the plate and crossing the central plane of the plate to the opposite side of the plate and there folded again along a plane at right angles to the axis of the plate.
8. An electric condenser including a plate, a boss formed on each side of said plate from the metal of the plate, the metal 6 of the plate being folded in one direction along the longitudinal axis of the plate and then folded back in the opposite direction along the axis of the plate and crossing the plane of the plate to the opposite side of the 7 plate and folded again on the last mentioned side along a plane at right angles to the axis of the plate, said boss being in the form of a cup, the plane through the center of the plate and parallel to the plate cutting the cup between its rim and bottom, the axis of the cup being parallel to the axis of the plane.
- In witness whereof, I have hereunto set my hand this 25th day of September, 1923.
- RALPH H. LANGLEY.
